United States Patent Office

Des. 194,643
Patented Feb. 19, 1963

194,643

METERING PUMP

Glenn E. Gould, Lansdale, Pa., assignor to William M. Wilson's Sons, Inc., Lansdale, Pa., a corporation of Pennsylvania

Filed May 29, 1962, Ser. No. 70,348

Term of patent 7 years

(Cl. D65—1)

FIG. 4.

FIG. 5.

FIG. 6.

FIG. 1 is a front elevational view of a metering pump, showing my new design;

FIG. 2 is a rear elevation of the pump;

FIG. 3 shows the pump in top plan;

FIGS. 4 and 5 respectively, show the pump as seen from the left and from the right of FIG. 1; and

FIG. 6 shows the pump in bottom plan.

I claim:

The ornamental design for a metering pump, as shown.
